UNITED STATES PATENT OFFICE.

THOMAS KEARNY VERTNER, OF RICHMOND, VIRGINIA.

TOP FOR ASH-CANS.

1,044,306.

Specification of Letters Patent.

Patented Nov. 12, 1912.

Application filed May 25, 1912. Serial No. 699,759.

To all whom it may concern:

Be it known that I, THOMAS KEARNY VERTNER, a citizen of the United States, residing at Richmond, in the county of Henrico and State of Virginia, have invented certain new and useful Improvements in Tops for Ash-Cans, of which the following is a specification, reference being had therein to the accompanying drawings.

This invention relates to a top for an ash can and similar receptacles, and has for its object the production of an efficient means whereby the door journaled to said top is normally held in a closed position.

Another object of this invention is the production of a means for guiding the ashes and other refuse upon the door.

With these and other objects in view this invention consists in certain novel combinations, constructions, and arrangement of parts as will be hereinafter fully described and claimed.

In the accompanying drawings:—Figure 1 is the perspective view of the top attached to a receptacle. Fig. 2 is a transverse section through the top. Fig. 3 is a rear view of the top showing the door in position. Fig. 4 is a blank view of the door.

Referring to the accompanying drawings by numerals 1 designates a receptacle upon which is mounted the top 2. This top 2 is provided with the flange 3 which is adapted to fit upon the upper portion of the receptacle 1 and hold the top thereon. The top 2 is provided with a rectangular opening 4 which is adapted to be closed by the door 5. The portion stamped from the top 2 is rolled back and forms an inverted U-shape guide 6. Positioned on the opposite side of the rectangular opening 4 is a slanting guide 7, which guide also forms a casting for the elongated weight 8 carried by the door 5. A guide 9 which is provided with the laterally extending flange 10, is positioned at each end of the rectangular opening 4 and at right angles with the inverted U-shape guide 6. This guide is adapted to close the space between the U-shape guide 6 and the slanting guide 7, and is held in such position by means of the rivets 11.

It will be seen that since the inner face of the inverted U-shape guide 6 and two end guides 9 extend at right angles relative to the rectangular opening 4 all the refuse which is emptied into the can will

have a clear drop upon the door. It is further obvious that the strain upon the rivets 11 is greatly reduced since one end of the guide 9 conforms to the contour of the inverted U-shape guide 6 and the other end tapers down and abuts against the slanting guide 7 and in this manner eliminates the longitudinal movement of said guide.

The door 5 is formed from a blank and has a rectangular body portion provided on one side with a reduced portion 12. It will be seen that this reduced portion 12 is bent to form a pocket for the elongated weight 8. The outer edges of the body portion are scored as shown at 13 so that said edges may be easily bent back to prevent any cutting edges upon the door. A plate 14 made in the form of a sleeve is riveted to the door 5 adjacent the reduced portion 12, and is journaled upon the journal pin 15, and in this manner forms an efficient means for allowing the door to operate. The outer ends of the journal pin 15 pass through the flange 3 and rest in the elongated reinforcing plates 16.

It will be seen that by use of the guiding portions formed upon the top of the can, when the ashes or other refuse is thrown upon the door, any particles that may happen to drop to one side of the rectangular opening will be guided upon the door by means of these portions. It will also be seen that by use of the weight mounted upon the rear portion of the door, said door will always be normally held in a closed position, but when it is desired to throw something into the can the weight will be raised into the slanting guide 7 and be held in such a position as will place it entirely out of the way of any refuse that may be in the can at the time.

By carefully considering Fig. 1, it will be seen that the guide 6 is formed from the material cut from the opening 4 and by bending the guide 6 in the manner as illustrated in Figs. 1 and 2 it will be seen that a very efficient guiding member has been produced for directing ashes or other material to the opening 4.

From the foregoing description it will be seen that a very efficient and simple device has been produced which may be made of sheet metal and thereby may be manufactured at a minimum cost. It will also be seen that the top 2 is provided upon its flange 3 with lifting handles 17 whereby the

top may be taken off the can when so desired.

Having thus described the invention what is claimed as new, is:—

- 5 1. In a receptacle of the class described, comprising a body portion, a top mounted upon said body, a flange formed upon said top and adapted to engage the upper side of said body, a rectangular opening formed in said top, guiding portions formed upon the opposite sides of said opening, a door carried by said top, an elongated weight carried by said door, reinforcing plates carried by said flange, a journal pin carried by said 10 top having its outer ends journaled in said reinforcing plates, a plate bent to form a sleeve mounted upon said journal pin and riveted to said top, whereby the door is held in an operable position in said top and 15 20 25 adapted to be automatically closed by said elongated weight.
2. In a receptacle of the class described comprising a body portion, a top mounted upon said body portion, said top provided with an opening, a substantially U-shape

guide formed from the portion cut to form said opening, a slanting guide mounted upon the opposite side of said opening and adapted to form a casing, a door mounted upon said top, and a weight carried by said door and entering said casing upon the opening of said door.

3. A receptacle of the class described comprising a body portion, a top mounted upon said body, said top provided with an opening, a door carried by said top and adapted to close said opening, said door formed from a blank comprising a body portion provided upon one side with a reduced portion, a weight carried by said door and adapted to hold the same in a closed position, the reduced portion of said door being bent to form a pocket for holding said weight in position.

In testimony whereof I hereunto affix my signature in presence of two witnesses.

THOMAS KEARNY VERTNER.
